UNITED STATES PATENT OFFICE.

EDWARD C. CARRIS AND VINCENT F. EPPEL, OF WASHINGTON, IOWA; SAID CARRIS
ASSIGNOR TO SAID EPPEL.

RADIATOR-HOLDING MACHINE.

Application filed May 10, 1921. Serial No. 468,453.

To all whom it may concern:

Be it known that we, EDWARD C. CARRIS and VINCENT F. EPPEL, citizens of the United States, and residents of Washington, 5 in the county of Washington and State of Iowa, have invented certain new and useful Radiator-Holding Machines, of which the following is a specification.

The object of our invention is to provide 10 a machine of simple, durable and inexpensive construction for holding radiators for repair purposes.

It is well-known that it is frequently desirable in repairing radiators and especially 15 where the tubes of the radiators leak to place the radiator in a tank of water, force air into the radiator for thereby locating the leaks, remove the radiator from the tank, close the holes in the tubes with solder.

20 It is our object more particularly to provide a machine for the convenient handling and manipulating of the radiator during such repair process.

25 For accomplishing this purpose, it is therefore our object to provide a machine, which may have a suitably mounted tank with mechanism thereon for supporting the radiator in a great variety of positions and for readily moving the radiator to its different positions.

30 With these and other objects in view, our invention consists in the construction, arrangement and combination of the various parts of our device, whereby the objects contemplated are attained, as hereinafter more fully set forth, pointed out in our claims, and illustrated in the accompanying drawings, in which:

35 Figure 1 shows a side elevation of a radiator holding machine embodying our invention, part of the tank being broken away to illustrate parts of the machine.

40 Figure 2 shows a top or plan view of the same.

45 Figure 3 shows a detail, sectional view taken on the line 3-3 of Figure 2.

Figure 4 shows a detail, sectional view taken on the line 4-4 of Figure 1.

50 Figure 5 shows an inverted plan view of the radiator holding arms; and

Figure 6 shows a detail, sectional view taken on the line 6-6 of Figure 4.

In the accompanying drawings, we have used the reference numeral 10 to indicate

generally a tank, which may be made of 55 galvanized iron or any suitable material.

The tank 10 is supported by legs 11, which may be made of angle irons. Suitable braces 12 may be provided.

On the upper outer portion of the tank 60 at one side thereof are spaced supporting brackets 13 and 14 on which are formed bearings 15, 16, 17 and 18 for parallel transverse shafts 19 and 20.

On the shaft 20 is a crank handle 21. 65 On the shaft 20 is a gear 22, which meshes with the gear 23 on the shaft 19. One end of the shaft 19 projects beyond the tank 10. Fixed on the projecting end of the shaft 19 is an arm 24 having at one 70 end a right-angled extension 25, forming bearings for a shaft 26.

Mounted at the other end of the arm 24 is a projecting shaft 27 on which is slidably mounted a counter-weight 28, which 75 may be adjusted to different positions on the shaft 27 and may be locked in its different positions by means of a set screw 29.

On one end of the shaft 26 is mounted a fitting 30 which forms a bearing for an 80 upright shaft 31. Mounted on the lower end of the upright shaft 31 is a cross bar 32.

The upper end of the shaft 31 is screw-threaded, as at 33, to receive an adjusting 85 tail nut 34. Between the nut 34, and the fitting 30, we preferably place a metallic washer 35, which is fixed with a key slidably located but not rotatably on the shaft 31.

90 It will be seen that by tightening the nut 34, the cross arm 32 may be gripped against the fitting 30 and the shaft 31 may thereby be held against rotation in the fitting 30.

95 The nut 34 may be loosened whereupon the shaft 31 may be rotated in the fitting 30 and the cross bar 32 may thus be adjusted to a variety of positions.

In Figure 2, we have shown the cross bar 32 in one position in full lines and in 100 another position in dotted lines.

105 It may be mentioned that the outer end of the shaft 26 is screw-threaded and has a tail nut 34^a, similar in construction and arrangement to the tail nut 34. The nuts 34 and 34^a are provided with projecting handles 34^b, so that they may be easily adjusted.

Mounted at the outer ends of the cross bar 32 are downwardly hanging rods or the like 36. Mounted rotatably in the lower end of one of the rods 36 is a cross shaft 37. Rotatably mounted in the lower end of the other rod 36 is one end of an aligned cross shaft 38. On the shaft 38 on the inside of the rod 36 is fixed a collar 39, while on the outer end of the shaft 38 is mounted a tail nut 34 similar to that already described, whereby the shaft 38 may be locked against rotation with relation to the rod 36, when desired.

The inner adjacent ends of the shafts 37 and 38 are secured into a fitting 40 and terminate short of each other.

In the fitting 40 is rotatably mounted a normally upright short shaft 41, having at its upper end an annular shoulder 42, bearing against the upper end of the fitting 40.

Projecting laterally from the upper end of the shaft 41 are arms 43. There are three of the arms 43 and they project radially from the shaft 41.

The lower end of the shaft 41 is screw-threaded as at 44 and receives a tail nut 34 similar to the tail nuts already described.

The arms 43 are provided with longitudinally elongated slots 45. Slidably mounted on the arms 43 are arms 46 which are adjustably held on the arms 43 by means of bolts 47 extended through the slots 45 and screwed into the arms 46. On the outer ends of the arms 46 are vertical bearings 48 in which are slidably mounted upright members 49, which may be locked in various adjusted positions by means of set screws 50.

On the upper ends of the uprights 49 are inwardly projecting fingers 51.

On the shaft 20 is an annular disc 53 around which extends a flexible brake band 54, which may be manipulated by means of a brake lever 55 pivoted on a bracket 56.

In the practical use of our improved radiator holding machine, the device may be moved from its position shown in full lines in Figure 1 to its position shown by dotted lines A in said figure, where the radiator gripping elements are entirely outside of the tank. The tail nut 34^a may be loosened during the swinging movement of the parts so that the members 36 will always remain in upright position.

The radiator is placed on the arms 46 and these arms are adjusted inwardly until the radiator is gripped by the members 49.

The tail nut 34 on the shaft 38 may be loosened and the radiator adjusted to any desired position and the tail nut may then be locked. Further adjustment may be had by rotating the short shaft 41.

The parts may be then swung from their dotted line position illustrated at A in Figure 1 to their full line position in Figure

1, whereupon the radiator will be in the tank and may be tested for leaks.

It will be noted that the construction of our device is such that the radiator may be adjusted to practically any desired position. For instance, in Figure 4, we have shown in dotted lines the radiator holding members arranged in position to hold the radiator tilted from the horizontal. This tilting movement is accomplished by loosening the tail nut 34 on the shaft 38 and rotating the shafts 37 and 38 and then locking the tail nut.

The arm 34 may be swung around to different positions, as illustrated for instance in Figure 2, where the arm 32 is shown in one position in full lines and in another position in dotted lines.

It will also be noted that there is nothing above the radiator to obstruct the clear and full inspection thereof.

Our machine is of simple construction and has such flexibility of operation as to permit any desired adjustment of the position of the radiator, and to lock and hold it in such position within the tank while being tested for leaks and without the tank while the leaks are being soldered.

Some changes may be made in the arrangement and construction of the various parts of our device, without departing from the essential features and purposes of our invention, and it is our intention to cover by our claims, any modified forms of structure or use of mechanical equivalents, which may be reasonably included within their scope.

We claim as our invention:

1. In a machine of the class described, a member mounted to move up and down above a tank and from position above the tank to position laterally of the tank and back, a yoke rotatably supported on said member to hang in vertical position in the various positions of the member, a holding element supported on said yoke for pivotal adjustment on two substantially intersecting axes.

2. In a device of the class described, a tank, an arm pivotally mounted outside said tank, a member on said arm adapted to project over the tank, a cross bar on said member, downwardly hanging elements on said bar, a radiator holding device supported by said elements.

3. In a device of the class described, a tank, an arm pivotally mounted outside said tank, a member on said arm adapted to project over the tank, a cross bar adjustably mounted on said member, downwardly hanging elements on said bar, a radiator holding device supported by said elements for adjustment in different planes.

4. In a device of the class described, a tank, an arm pivotally mounted outside said tank, a member on said arm adapted to project over the tank, a cross bar pivotally

mounted on said member, means for locking said bar against pivotal movement, downwardly hanging elements on said bar, a radiator holding device supported by said elements.

5. In a machine of the class described, a member mounted to move up and down above a tank and from position above the tank to position laterally of the tank and 10 back, a yoke rotatably supported on said member to hang in vertical position in the various positions of the member, a holding element supported on said yoke for pivotal adjustment on two substantially intersecting 15 axes, and means for locking said locking element in various positions of its adjustment on either axis.

6. In a device of the class described, a tank, a shaft mounted thereon, an arm on 20 said shaft adapted to swing in a plane outside of the tank, a second shaft rotatably supported on said arm and adapted to project over the tank, and a radiator holding means hung from said second shaft, and 25 means for locking said second shaft against rotation.

7. In a device of the class described, a tank, a shaft rotatably supported on said tank on the outside thereof, means for imparting rotation to said shaft, an arm on 30 said shaft arranged outside said tank, a shaft supported on said arm and designed to project over said tank in certain positions of said arm, adjustable means for locking said second shaft against rotation, a bar pivotally mounted on said second shaft, means for locking said bar against pivotal movement, downwardly hanging members on said bar, a supporting device rotatably mounted on the lower ends of said downwardly hanging members, means for locking 35 said supporting device against rotary movement, a shaft supported by said supporting device for rotation, means for locking said last shaft against rotation, radially extending arms on said last shaft, gripping members adjustably mounted on said last-described arms, and provided with adjustable gripping elements.

8. In a device of the class described, a tank, a shaft rotatably supported on said tank on the outside thereof, means for imparting rotation to said shaft, an arm on said shaft arranged outside said tank, a shaft supported on said arm and designed to project over said tank in certain positions of said arm, adjustable means for locking said second shaft against rotation, a bar pivotally mounted on said second shaft, means 50 for locking said bar against pivotal movement, downwardly hanging members on

said bar, a supporting device rotatably mounted on the lower ends of said downwardly hanging members, means for locking said supporting device against rotary movement, a shaft supported by said supporting device for rotation, means for locking said last shaft against rotation, radially extending arms on said last shaft, gripping members adjustably mounted on said last-described arms and provided with adjustable gripping elements, and a counterweight adjustably supported on said first arm.

9. In a device of the class described, a support, a horizontal shaft rotatably mounted thereon, an arm fixed to said shaft to swing in a vertical plane, a laterally extending shaft supported on said arm for rotation, means for locking said laterally extending shaft against rotation, a bar supported on 80 said laterally extending shaft transversely with relation thereto for pivotal swinging movement, means for locking said bar against such movement, downwardly hanging members on said bar, a transverse supporting element on said members rotatably mounted, means for locking said last element against rotation, a shaft mounted on said last element at right angles thereto for rotation, means for locking said last shaft 90 against rotation, radially extending arms on said last shaft, engaging elements adjustably mounted on said last-named arms having adjustable gripping members.

10. In a device of the class described, a support, a horizontal shaft rotatably mounted thereon, an arm fixed to said shaft to swing in a vertical plane, a laterally extending shaft supported on said arm for rotation, means for locking said laterally extending shaft against rotation, a bar supported on 100 said laterally extending shaft transversely with relation thereto for pivotal swinging movement, means for locking said bar against such movement, downwardly hanging members on said bar, a transverse supporting element on said members rotatably mounted, means for locking said last element against rotation, a shaft mounted on said last element at right angles thereto for rotation, means for locking said last shaft 105 against rotation, radially extending arms on said last shaft, engaging elements adjustably mounted on said last-named arms having adjustable gripping members, a shaft parallel with said first shaft, coacting gearing devices on said first and last shafts, and a brake device operatively connected with said last shaft.

Des Moines, Iowa, May 2, 1921.

EDWARD C. CARRIS.
VINCENT F. EPPEL.
